LASTING DEVICE

Lloyd G. Miller, Beverly, Mass., assignor to
 United Shoe Machinery Corporation, Flemington, N. J., a corporation of New Jersey

Application May 17, 1946, Serial No. 670,505

16 Claims. (Cl. 12—9)

1
 This invention relates to lasting devices and particularly to a device for use in lasting the forepart of a shoe with adhesive.

In the lasting of certain types of shoes, for example, women's Littleway lasted shoes, it is a common practice in the trade to secure the upper in the shank portion of the shoe, i. e., from the breast line to, or just beyond the ball line, to the insole, with metallic fasteners, such as staples, and to use adhesive for securing the upper in the forepart from the ball line to the tip line. In following this procedure, the operator usually takes the shoe, the upper of which has been previously assembled and pulled over, spindles the upper by hand on the opposite sides of the shoe at the ball line and breast line respectively, and then lasts the shoe in its shank portion by means of a staple side-lasting machine of a type which is illustrated in United States Letters Patent No. 1,815,295, issued on July 21, 1931, in the name of George Goddu. The unlasted upper at the forepart, from the ball line to the tip line, or to the rearmost pulling-over tack, on the opposite sides of the shoe, is then laid over against the shoe bottom without any lasting stress being applied thereto and secured adhesively to the insole by means of hammer blows applied thereto. Inasmuch as the lasting stresses of the previous pulling-over and shank-lasting operations have, at least to some degree, extended to the forepart, no substantial amount of additional tensioning is required and the results of the above outlined procedure for lasting the forepart, while not entirely satisfactory, are acceptable to the trade. However, some looseness of the upper on the last will remain along the opposite sides of the shoe and the pounding of the upper, to secure it to the insole, will aggravate this condition.

It is an object of this invention to provide a simple and easily usable device by means of which the forepart of a shoe of the above-mentioned type may be lasted readily and quickly and in a more satisfactory manner than by the procedure explained above. To this end, the herein illustrated device, which is intended primarily for use in conjunction with a staple side-lasting machine, is provided with a gripper comprising a pair of jaws for taking hold of the lasting margin of the upper at the forepart with a frictional grip so that lasting stress may be applied thereto by moving the shoe away from the gripper, and a heated wiper positioned adjacent to the gripper for laying that portion of the lasting margin of the upper which extends substantially from the ball line to the tip line smoothly against the bot-

2
 tom of the shoe as the shoe is moved away from the gripper. Preferably, and as herein illustrated, the gripper is provided with a yielding closing means, adapted to be operated by the pressure of the shoe bottom thereagainst, so that the upper may be yieldingly seized, then tensioned, by movement of the shoe away from the gripper, and finally wiped smoothly over the shoe bottom, and secured thereto by the adhesive, as the movement of the shoe is continued.

The above and other objects and features of the invention will be apparent from the following detailed description of the preferred embodiment thereof illustrated in the accompanying drawings and will be pointed out in the claims.

In the drawings,

Fig. 1 is a view in side elevation, with certain portions in section, of a device embodying the features of this invention;

20 Fig. 2 is a view similar to that of Fig. 1, but showing the positions of the parts at a different stage in the operation of the device;

Fig. 3 is a view similar to Fig. 1, but showing the position of the parts in a still different stage 25 in the operation of the device;

Fig. 4 is a plan view of a shoe which has been pulled over and lasted in the shank with staples prior to the lasting of its forepart; and

Fig. 5 is a plan view of the device shown in 30 Fig. 1 with a portion of a shoe shown in broken lines and in the position assumed at the completion of the forepart-lasting operation.

Referring to the drawings, and especially Figs. 1 to 3 thereof, the reference character 10 indicates 35 an overhanging portion of a support which may be of any suitable construction and adapted to be mounted on a bench or, if desired, attached to the frame of a staple side-lasting machine of the type illustrated in the above-mentioned Goddu

40 patent. Secured to the lower side of the support 10, by means of screws 12, is a fixed wiper plate 14 the forward end of which is shaped to fit around the support and provided, at its mid-portion, with serrations, or teeth, 16, to form a gripper jaw 18.

45 Another gripper jaw 20, which is likewise provided with serrations, or teeth, 22, extends downwardly from a bifurcated hub 24 that is rotatably mounted on a shaft 26 carried by the support 10, see Fig. 5. Also rotatably mounted on this shaft is 50 a hub 28, positioned between the bifurcations of the hub 24, and from which extends a curved gripper-closing finger 30, a compression spring 32 being interposed between the finger 30 and the gripper jaw 20. A pin 40 is screwed into the hub 55 28 and a tension spring 42 is stretched between

this pin and another pin 44 that is secured to a cross member 46 of the support 10. The hub 28 is formed with a hook portion 50 that is adapted to engage the jaw 20 and hold it away from the jaw 18 when the parts are in the positions shown in Fig. 1, the finger 30 being at this time swung in a clockwise direction, by the spring 42, until the pin 40 engages a second cross member 52 of the support 10. For heating the wiper plate 14, an electrical heating unit, indicated by the reference character 69, is positioned in back of and in direct contact with the wiper plate. This unit may be of any desired type and suitable thermostatic controls, not shown, may be provided for regulating the temperature of the wiper plate. Preferably, the front edge of the wiper plate 14 is curved, as indicated at 62, Fig. 5, so as to conform approximately to the contour of the shoe bottom at the forepart.

In using the device to last the forepart of a shoe, such for example as the shoe illustrated in Fig. 4, the upper U of which has been pulled over at the toe and secured by means of tacks t—t, and lasted in the shank portion with staples s—s, the unlasted portion of the upper at the forepart on one side of the shoe, indicated by the reference character F, is inserted between the open jaws 18 and 20 with these jaws centered approximately in a lengthwise direction with respect to the extent of the unlasted portion F, and with the shoe held by the operator so that its bottom is inclined downwardly toward the device, see Fig. 1. The shoe is now lifted and swung somewhat in a counterclockwise direction to bring its bottom nearly parallel to the surface of the wiping plate 14. Such upward movement of the shoe will swing the finger 30 in a counterclockwise direction, and this movement of the finger 30 will, through the action of the compression spring 32, close the jaws 18 and 20 yieldingly on the lasting margin of the upper, see Fig. 2. Now, as the shoe is moved inwardly away from the gripper and toward the device, in the direction of the arrow in Fig. 2, the upper will be tensioned over the last L. At first, the shoe should be held with its bottom not quite parallel to the wiper surface so that the upper materials may be fully tensioned before wiping. As this inward movement is continued the shoe is turned to bring its bottom parallel to the surface of the fixed wiper 14 so that the lasting margin as it is pulled out of the yielding closed jaws 18 and 20 will be wiped smoothly over and pressed firmly against the insole I, see Figs. 3 and 5. It will be understood that the lasting margin of the upper in the forepart will have been previously coated with a suitable adhesive so that the wiping and pressing action, as above explained, will result in its being securely fastened to the insole, this effect being, of course, facilitated by the action of the heated wiper. This operation is then repeated on the other side of the shoe to complete its side lasting.

The operation of lasting the forepart of a shoe with the illustrated device may be very quickly and satisfactorily accomplished by means of a few simple movements of the shoe by the operator, and yet, because of the action of the grippers, the upper will be adequately tensioned and this tensioning effect may be varied, as desired, by a slight rocking movement of the shoe or a change in the upward pressure of the shoe against the finger 30, to suit different operating conditions. Also, with the device located adjacent to, or even supported directly on, a staple side-lasting machine, the whole side-lasting operation may con-

veniently be performed with one handling of the shoe, the shoe being first spindled and lasted in the shank in the usual manner and then presented to the forepart lasting device for lasting the forepart all as one substantially continuous operation. After the forepart, at the opposite sides of the shoe, has been lasted, the heated wiper plate may be used as an ironing member for smoothing the overlasted margin of the upper at other locations along the bottom of the shoe.

Having described the invention, what I claim as new and desire to secure by Letters Patent of the United States is:

1. A device for use in lasting a shoe having, in combination, a gripper comprising a pair of jaws, means for closing the jaws on the lasting margin of the upper of a shoe, and a fixed wiper positioned adjacent to the gripper for laying the lasting margin of the upper against the shoe bottom as the shoe is moved away from the gripper to tension the upper by pulling it out of the gripper.
2. A device for use in lasting a shoe having, in combination, a gripper comprising a pair of jaws, means for closing the jaws on the lasting margin of the upper of a shoe in response to pressure of the shoe bottom on said gripper-closing means, and a wiper positioned adjacent to the gripper for laying the lasting margin of the upper against the shoe bottom as the shoe is moved away from the gripper, by an operator, to tension the upper.
3. A device for use in lasting the forepart of a shoe having, in combination, a gripper comprising a pair of jaws, means for yieldingly closing the jaws on the lasting margin of the upper of a shoe, and a fixed wiper positioned adjacent to the gripper for laying the lasting margin of the upper against the shoe bottom as the shoe is moved away from the gripper to tension the upper by pulling it out of the gripper.
4. A device for use in lasting the forepart of a shoe having, in combination, a gripper comprising a pair of jaws, means for yieldingly closing the jaws on the lasting margin of the upper of a shoe in response to pressure of the shoe bottom on said gripper-closing means, and a wiper positioned adjacent to the gripper for laying the lasting margin of the upper against the shoe bottom as the shoe is moved away from the gripper, by an operator, to tension the upper.
5. A device for use in lasting a shoe with adhesive having, in combination, a gripper comprising a pair of jaws, means for closing the jaws on the lasting margin of the upper of a shoe, and a fixed heated wiper positioned adjacent to the gripper for laying the lasting margin of the upper against the shoe bottom as the shoe is moved away from the gripper to tension the upper by pulling it out of the gripper.
6. A device for use in lasting a shoe with adhesive having, in combination, a gripper comprising a pair of jaws, means for closing the jaws on the lasting margin of the upper of a shoe in response to pressure of the shoe bottom on the gripper-closing means, and a heated wiper positioned adjacent to the gripper for laying the lasting margin of the upper against the shoe bottom as the shoe is moved away from the gripper, by an operator, to tension the upper.
7. A device for use in lasting a shoe with adhesive having, in combination, a gripper comprising a pair of jaws, means for yieldingly closing the jaws on the lasting margin of the upper of a shoe, and a fixed heated wiper positioned adjacent to the gripper for laying the lasting margin of the upper against the shoe bottom as the shoe

is moved away from the gripper to tension the upper by pulling it out of the gripper.

8. A device for use in lasting a shoe with adhesive having, in combination, a gripper comprising a pair of jaws, means for yieldingly closing the jaws on the lasting margin of the upper of a shoe in response to pressure of the shoe bottom on said gripper-closing means, and a heated wiper positioned adjacent to the gripper for laying the lasting margin of the upper against the shoe bottom as the shoe is moved away from the gripper, by an operator, to tension the upper.

9. A device for use in lasting the forepart of a shoe having, in combination, a gripper comprising a pair of jaws, means for closing the jaws on the lasting margin of the upper of a shoe, and a fixed wiper positioned adjacent to the gripper for laying that portion of the lasting margin of the upper extending substantially from the ball line to the tip line against the shoe bottom as the shoe is moved away from the gripper to tension the upper by pulling it out of the gripper.

10. A device for use in lasting the forepart of a shoe having, in combination, a gripper comprising a pair of jaws, means for closing the jaws on the lasting margin of the upper of a shoe in response to pressure of the shoe bottom on said gripper-closing means, and a wiper positioned adjacent to the gripper for laying that portion of the lasting margin of the upper extending substantially from the ball line to the tip line against the shoe bottom as the shoe is moved away from the gripper, by an operator, to tension the upper.

11. A device for use in lasting the forepart of a shoe having, in combination, a gripper comprising a pair of jaws, means for yieldingly closing the jaws on the lasting margin of the upper of a shoe, and a fixed wiper positioned adjacent to the gripper for laying that portion of the lasting margin of the upper extending substantially from the ball line to the tip line against the shoe bottom as the shoe is moved away from the gripper to tension the upper by pulling it out of the gripper.

12. A device for use in lasting the forepart of a shoe having, in combination, a gripper comprising a pair of jaws, means for yieldingly closing the jaws on the lasting margin of the upper of a shoe in response to pressure of the shoe bottom on said gripper-closing means, and a wiper positioned adjacent to the gripper for laying that portion of the lasting margin of the upper extending substantially from the ball line to the tip line against the shoe bottom as the shoe is moved away from the gripper, by an operator, to tension the upper.

13. A device for use in lasting the forepart of a shoe with adhesive having, in combination, a gripper comprising a pair of jaws, means for closing the gripper on the lasting margin of the upper of a shoe, and a fixed heated wiper positioned adjacent to the gripper for laying that portion of the lasting margin of the upper extending substantially from the ball line to the tip line against the shoe bottom as the shoe is moved away from the gripper to tension the upper by pulling it out of the gripper.

14. A device for use in lasting the forepart of a shoe with adhesive having, in combination, a gripper comprising a pair of jaws, means for closing the gripper on the lasting margin of the upper of a shoe in response to pressure of the shoe bottom on said gripper-closing means, and a heated wiper positioned adjacent to the gripper for laying that portion of the lasting margin of the upper extending substantially from the ball line to the tip line against the shoe bottom as the shoe is moved away from the gripper, by an operator, to tension the upper.

15. A device for use in lasting the forepart of a shoe with adhesive having, in combination, a gripper comprising a pair of jaws, means for yieldingly closing the jaws on the lasting margin of the upper of a shoe, and a fixed heated wiper positioned adjacent to the gripper for laying that portion of the lasting margin of the upper extending substantially from the ball line to the tip line against the shoe bottom as the shoe is moved away from the gripper to tension the upper by pulling it out of the gripper.

16. A device for use in lasting the forepart of a shoe with adhesive having, in combination, a gripper comprising a pair of jaws, means for yieldingly closing the jaws on the lasting margin of the upper of a shoe in response to pressure of the shoe bottom on said gripper-closing means, and a heated wiper positioned adjacent to the gripper for laying that portion of the lasting margin of the upper extending substantially from the ball line to the tip line against the shoe bottom as the shoe is moved away from the gripper, by an operator, to tension the upper.
